ALBERT H. NELLER, OF FAIRFIELD, IOWA, ASSIGNOR TO LOUDEN MACHINERY COMPANY, OF FAIRFIELD, IOWA, A CORPORATION OF IOWA.

OVERHEAD-TRACK SWITCH.

1,333,183.

Specification of Letters Patent.

Patented Mar. 9, 1920.

Application filed November 14, 1919. Serial No. 382,035.

To all whom it may concern:

Be it known that I, ALBERT H. NELLER, a citizen of the United States, residing at Fairfield, in the county of Jefferson and State of Iowa, have invented a new and useful Improvement in Overhead-Track Switches, of which the following is a specification.

My invention relates to that class of overhead track switches which are constructed with a portable frame which can be mounted in position without having to assemble the constituent parts of the switch, and it consists of an improvement in the construction and arrangement of the parts as herein described and as set forth in the claims.

In the accompanying drawings forming a part of this specification, Figure 1 is a perspective of an overhead track switch embodying my invention. Fig. 2 is a vertical cross section on line 2—2 of Fig. 1. Figs. 3 and 4 are enlarged detail views which will be hereafter explained.

Referring to the drawings, A represents a pair of metallic bars, preferably angular in cross section, which are joined together at their ends by castings B and C. The casting B is considerably narrower, or shorter laterally, than the casting C, whereby the bars A will be held at an angle to each other. The casting B is provided with a central upwardly arched body which is extended longitudinally of the switch frame and has a series of holes D which are preferably elongated, and are also disposed longitudinally in relation to the switch frame. The casting C is provided with an outwardly extended flange C' which is set in a plane higher than the body of the casting, and in this flange there are a series of preferably elongated holes E, the flange and the holes therein being slightly curved and disposed at approximately right angles to the side bars A.

The bars A and castings B and C form a frame for the switch mechanism which is connected to an overhead support, such as the ceiling of a building, (not shown in drawings) by bolts or screws passed through some of the holes D and E. These two series of holes being disposed at approximately right angles to each other, the switch frame may be readily adjusted to obtain proper bearings for the bolts to connect the frame to its overhead support. The

portions of the castings B and C having the bolt holes D and E, being set in a plane higher than other parts of the switch frame, also assists in making the connection.

On each side of the arched body of the casting B are laterally extended depressed lugs F. In each of these lugs there is a hole opposite a corresponding hole in the adjacent ends of the bars A, and in these holes bolts G are inserted to join the ends of the bars to the casting B. Immediately below the casting B is a hanger H having a bifurcated upper end and two laterally extended flanges each having a hole through which the bolts G are also passed, thus connecting the hanger H, the casting B and the adjoining ends of the bars A together.

I represents a portion of a track-rail for an elevated carrier to run upon, having its adjacent end connected to the hanger H in the usual manner, the remaining portions of the track-rail to be supported in position in any suitable manner known to the art. J represents a switch section of the track-rail which is connected to the main track section I, as shown in Fig. 1, by a hinge coupling K. The other end of the switch section is slidably connected to the casting C by means of a track hanger L attached to a switch casting M provided with a flange N adapted to catch over and slide on a rib O on the casting C.

The hanger L is substantially the same as the hanger H, with the exception of the hinge K, and is connected to the casting M by bolts passed through its upper bifurcated ends. The casting M is provided with a spring actuated bolt P having its adjacent end adapted to catch in a notch a in the rib or flange O, and thus hold the casting in position to bring the switch section J in line with one of the branch tracks Q, and prevent it from sliding on the rib or flange O. Two or more branch tracks Q may be used, the casting C being made of sufficient length to accommodate them, and the casting being provided with a notch a for each of the tracks, so that the switch section may be held in the proper position to connect with each of the branch tracks.

The adjacent ends of the branch tracks Q are connected to the casting C by hangers R having bolts b passed through their upper ends and through holes in the casting C, the other portions of the branch tracks being

supported by any suitable means known to the art. S represents stop devices to prevent a carrier from running off the end of the branch track when disconnected from the 5 switch section, the stop being lifted out of the way of the carrier when connected with the switch section, as already known in the art.

Fig. 3 is an enlarged plan view of the casting C showing its connection with the bars A, and the switch casting M, but not showing the branch tracks Q or the stop devices S. Also showing the heads of the bolts 7 connecting the hangers R to the casting C. 10 The adjacent ends of the side bars A are connected to outer portions of the casting C by bolts d. These portions of the casting C are preferably provided with flanges e which embrace the lower corners of the opposite 15 sides of the adjoining ends of the side bars A, and will hold them more rigidly in position.

The outer end of the latch bolt P is passed through a hole in an upturned flange or lug T on the outer portion of the switch casting M, and its inner end is passed through an opening in a central portion of the casting immediately under the inner edge of the flange N so it will be free to enter the notches a in the rib O, and to be withdrawn therefrom. The latch bolt P is operated by means of a trip U which is pivoted to an inner portion of the latch bolt by a bolt or rivet f.

Fig. 4 is a view of the under side of the trip U with a portion of the trip cord V connected, but detached from the latch bolt. It consists essentially of a laterally extending portion, pivoted to the latch bolt in its center, and provided on its extremities with downwardly extended points g, and two outwardly extending side portions h joined together at their outer ends so as to form an eye for the trip cord V.

In its normal position the points g will rest against the edges of the flange N, but a pull on the trip cord on one side will cause the point on the opposite side to move away from the flange N and slide on the adjacent side m of the switch casting M until it comes in contact with the adjacent stop i. This will cause the latch bolt P to be withdrawn from its engagement with the adjacent notch in the rib O, and the switch casting 50 will be free to slide along the rib O carrying with it the adjacent end of the switch section J until it connects with another branch track. A pull on the trip cord in the opposite direction will reverse the operation.

The outer portion of the trip U is bent downward so the eye where the trip cord is attached will be below the corresponding portion of the switch casting M and also the outer end of the latch bolt P. This arrangement brings it in line with small guide pul-

leys W which are connected to the lower edges of the side bars A. These pulleys are used to guide the trip cords in the proper direction to reach the operator. The lines V' in Fig. 1 indicate the usual direction in which the trip cords are disposed.

As arranged only a single cord is necessary. A central portion of the cord is doubled in a loop which is passed through the eye, as shown in Fig. 4, and this loop is then placed around inwardly projecting prongs k which will hold the cord securely in place without any additional fastenings.

In carrying heavy loads on a light track, it is necessary to have frequent supports. It is especially necessary that the switch section, which has to depend upon its own inherent strength without any assistance from a rigid connection with the adjoining portions of the track, be securely supported.

To strengthen the switch section J, I rivet or bolt a member X to the central portions of the side bars A so as to stand at approximately right angles thereto. The central portion of the member X is made essentially in the form of a lineal bar. I fasten a track hanger Y to the switch section directly below this member. The upper end of the hanger is adapted to catch over and slide on the central portion of the member as the switch section is being moved from one position to another. By this means the central portion of the switch section will be supported by the side bars of the switch frame, and, at the same time, it will be free to be moved from one position to another.

As shown in the drawing, the hanger is provided with a loop Z which surrounds the central portion of the member X and is free to slide thereon. The central upper edge of the member X is preferably rounded in cross section to fit the curve of the loop, while its lower edge is extended down in the form of a rib to give it greater strength. The ends of the member are preferably flattened for attachment to the side bars A.

What I claim is:

1. In overhead track switches having a portable frame, the combination of a pair of side-bars, a casting at each end of the bars having portions with a series of holes therein for suspending bolts, set in a plane higher than the other portions of the castings, and means to connect the ends of the side bars to the castings.

2. In overhead track switches having a portable frame, the combination of a pair of side-bars, a casting at each end of the bars having portions with a series of holes therein for suspending bolts, set in a plane higher than the other portions of the castings, said portions with the holes therein being horizontally disposed at an angle to each other, and means to connect the ends of the side-bars to the castings.

3. In overhead track switches having a portable frame, the combination of a pair of side bars, a casting at each end of the bars having portions with a series of holes therein for suspending bolts, set in a plane higher than the other portions of the castings, means to connect the ends of the side-bars to the castings so as to form a portable frame, and main and branch tracks with a coöperating switch section connected to said frame.

4. In a device of the character described, a portable frame consisting of side bars joined together near their ends, main and branch tracks with a coöperating switch section connected to said frame, and a support attached to a central portion of the switch section, and connected to a central portion of the switch frame and adapted to slide thereon.

5. In a device of the character described, a portable frame consisting of side bars joined together near their ends, main and branch tracks with a coöperating switch section connected to said frame, a cross bar connected to a central portion of the side bars, and a hanger attached to a central portion of the switch section, said hanger being adapted to be supported by and to slide on said cross bar.

6. In a device of the character described, a portable frame consisting of side bars joined together near their ends, main and branch tracks with a coöperating switch section connected to said frame, a cross bar connected to a central portion of the side bars, and a hanger connected to a central portion of the switch section, said hanger having a loop at its upper end adapted to catch over and slide on the cross bar.

7. In a device of the character described, a main track, a plurality of branch tracks, a switch section connected to the main track and adapted to aline with either of the branch tracks, a frame casting to which the adjoining ends of the branch tracks are connected, a switch casting adapted to slide on the frame casting and to which the free end of the switch section is connected, a spring actuated latch bolt carried by the switch casting and adapted to connect with the frame casting, and a trip, centrally connected to the latch bolt, mounted on the switch castings, said trip having downwardly projecting ends adapted to be moved on the switch casting whereby the latch bolt may be released from the frame castings, and the free end of the switch section may be moved from one branch track to another.

8. In a device of the character described, a main track, a plurality of branch tracks, a switch section connected to the main track and adapted to aline with either of the branch tracks, a frame casting to which the adjoining ends of the branch tracks are connected, a switch casting adapted to slide on the frame casting and to which the free end of the switch section is connected, a spring actuated latch bolt carried by the switch casting and adapted to connect with the frame casting, and a trip, centrally connected to the latch bolt, mounted on the switch casting, said trip having downwardly projecting ends adapted to be moved on the switch casting whereby the latch bolt may be released from the frame castings, and the free end of the switch section may be moved from one branch track to another.

9. In a device of the character described, a main track, a plurality of branch tracks, a switch section connected to the main track and adapted to aline with either of the branch tracks, a frame casting to which the adjoining ends of the branch tracks are connected, a switch casting adapted to slide on the frame casting and to which the free end of the switch section is connected, a spring actuated latch bolt carried by the switch casting and adapted to connect with the frame casting, and a trip, centrally connected to the latch bolt, mounted on the switch casting, and adapted to be moved thereon to release the latch bolt from the frame casting, the outer end of said trip being bent down under the outer ends of the switch casting and the latch bolt and being joined together to form a connection for a trip cord.

10. In a device of the character described, a main track, a plurality of branch tracks, a switch section connected to the main track and adapted to aline with either of the branch tracks, a frame casting to which the adjoining ends of the branch tracks are connected, a switch casting adapted to slide on the frame casting and to which the free end of the switch section is connected, a spring actuated latch bolt carried by the switch casting and adapted to connect with the frame casting, and a trip, centrally connected to the latch bolt, mounted on the switch castings, and adapted to be moved thereon to release the latch bolt from the frame casting, the outer end of said trip being bent down under the outer ends of the switch casting and the latch bolt and being joined together to form an eye for the insertion of a loop of a trip cord, and a prong over which the loop of the trip cord is placed.
